UNITED STATES PATENT OFFICE.

BURT S. HARRISON, OF CHICAGO, ILLINOIS, ASSIGNOR TO DRYING SYSTEMS, INC., OF CHICAGO, ILLINOIS, A CORPORATION OF ILLINOIS.

EQUALIZED DISTRIBUTION SYSTEM FOR FLUIDS.

Application filed November 23, 1921. Serial No. 517,308.

To all whom it may concern:

Be it known that I, BURT S. HARRISON, a citizen of the United States of America, and a resident of Chicago, county of Cook, 5 and State of Illinois, have invented a new and useful Improvement in Equalized Distribution System for Fluids, of which the following is a specification.

This invention relates in general to delivery or receiving conduits or nozzles, and is illustrated herein in a manner which is useful for the uniform delivery of air to or exhaust of air from a room throughout its length. In the drying art it is necessary 10 in order to attain uniform results upon all the goods in the drying room, to obtain a uniform circulation of air through the room at all points, that is, each unit of length of the room should be subject to 15 the same rate of air flow as every other such unit.

The objects of the present invention are to improve and simplify the construction of such delivery or exhaust conduits in 20 order to insure the desired result and eliminate the necessity of adjustments of any kind.

When fluids such as air or gas are caused 25 by a fan or blower, to flow through a duct having distributed outlets, it has generally been found difficult to so proportion the duct and its inlet or outlet orifices or nozzles to attain a uniform distribution or flow at all points. This difficulty is quite pro- 30 nounced when using the customary arrangement of stepped duct, that is, one having reducing or transformation portions between the various outlets along the same. Unless the friction which will occur in each 35 outlet and each transformation is exactly known there is a likelihood that the outlets nearest the fan will over-deliver, and to obtain even distribution requires the use of numerous dampers, and considerable testing 40 45 and adjustment is also required. This trouble becomes particularly apparent when long ducts having a great number of openings are employed. If the openings are proportioned throughout according to the frictional resistance, then no two such openings will be of the same size. Also, the shape and proportion of the transformation links, and the angle at which the outlet branches project from the duct greatly 50 55 affects the resistance.

The objects of the present invention are accomplished by a structure such as illustrated in the drawings, wherein—

Figure 1 is a plan view of a delivery duct constructed according to this invention 60 to deliver a continuous sheet of air of uniform thickness.

Figure 2 is an end view of the same.

Figure 3 shows the duct in side elevation.

Figures 4, 5 and 6 are similar views, but 65 illustrate a duct of circular cross section rather than the rectangular duct illustrated in Figures 1 to 3.

Figures 7, 8 and 9 illustrate a duct similar to the one shown in Figures 1 to 3, but 70 is designed with particular reference to exhausting rather than delivering air.

The present design of duct may vary considerably in cross sectional appearance, but for convenience of fabrication is preferably 75 either square or round as illustrated. Its principal characteristic feature is that it is tapered uniformly from one end to the other and has a slot in one side extending the entire length of the delivery portion of the duct. An apron covers the slot and is tapered throughout its length in a manner corresponding to the variation in the duct dimensions. The apron is supported by 80 partitions or withes regularly spaced, and extending from the front to the back edge of the apron. This apron affords means for uniformly varying the resistance to the flow of the air or other fluid at the outlets, and in complementary correspondence to the resistance encountered at various points throughout the length of the duct so that the resultant pressure at the outlet (velocity head) is the same for every unit of outlet 85 90 95 length.

The present design takes into consideration the various losses in pressure due to dynamic action and friction. The dynamic losses are the velocity head or power to cause the fluid to enter the duct, losses due to 100 change of direction, and losses due to change of velocity as in transformation. The friction losses are all due to the friction of the fluid against the walls of the duct. Pressure, temperature and density of the air effect the losses, but in the same duct system these need not vary. The pressure loss due to dynamic action is of course much affected by the form of the duct. The easier and more uniform the transformation of either direc- 105 110

tion or velocity, the less the loss. With this in mind, the present duct is uniformly tapered from end to end, and from the fact that the friction losses vary directly with the 5 length of the duct, inversely as the diameter of the duct, and directly as the square of the air velocity, the frictional resistance arranged for at different points along the length of the duct by the apron is made to 10 complement these losses to insure equal deliveries at different points throughout the length of the duct. In this manner by an extremely simple design, uniform delivery with respect to both volume and velocity at 15 different points along the length of the duct is insured.

As illustrated in Figures 1 to 3, the delivery duct may be formed from sheet metal, with the rectangularly arranged walls 1, 2, 3, 20 and 4, these walls being of gradually decreasing width so as to provide the desired taper. The wall 4 at its rear edge 5 terminates short of the wall 1, to provide the outlet opening 6. The edge 5 of the wall 4 is 25 turned over the wire 7 to eliminate vibration and avoid a sharp edge around which the air must travel in its change of direction between the duct and the outlet 8. This outlet is covered by an apron 9 attached to 30 the wall 1 and extending parallel with the wall 4, and uniformly spaced outwardly therefrom. The outlet 8 is subdivided by equally spaced partitions 10 between the apron 9 and the wall 4.

35 In the tapered form of duct as illustrated, the velocity of flow through the slot 8 may be of constant value throughout the length of the duct, or if desired, gradually and uniformly diminished from the large end to the 40 small end. This is due to the fact that the frictional resistance within the duct gradually increases from the large end to the small end of the duct since frictional resistance in the duct varies inversely as the diameter 45 and directly as to length of the duct. By properly proportioning the width and taper of the apron, and its distance from the wall 4, the outlet friction can be made to supplement the duct friction in any desired way.

50 At the large end of the duct in the form shown in Fig. 1 the duct friction is least and the outlet friction is greatest due to the length (width) of the apron, just as friction in any duct varies with the length of the 55 duct. At the small end of the duct the duct friction loss is greatest due to its small diameter and distance from the fan, but the outlet friction loss is least because the apron is shortest (narrowest) at this point. The 60 sum of the duct friction loss and the outlet friction loss is the same at any point along the length of the duct, and as the area of the outlet is uniform per unit of length, the delivery of the different units of length of the 65 outlet will be the same as to both volume

and velocity throughout the length of the duct. It may be seen that the dimensions of the duct if designed according to the present plan may be readily correctly determined for any desired result.

70 The frustoconical duct or nozzle illustrated in Figures 4 to 6 is designed according to the same plan, tapering from end to end and providing frictional resistance at the outlets which complements the frictional resistance at the corresponding portion of the duct. This form may be rolled from a single sheet of metal, giving the spiral cross sectional appearance illustrated in Figure 5, the outlets 11 being arranged for by the overlapping ends 12 and 13 of the body part 14. 75 The outlets are separated by the spacers 15.

The exhaust duct shown in Figures 7 to 9 is similar in design to the delivery duct illustrated in Figures 1 to 3 except that its taper is less, and the apron 16 while tapering in correspondence with the duct, is spaced in inclined relation to the duct the space being gradually narrowed toward the large end of the duct. When air 90 is being delivered from the duct by pressure, the taper on the duct may be greater than when the air is being exhausted through the duct, on account of the development of static pressure in the duct, that is, the velocity in the duct can be maintained practically uniform throughout the duct in a pressure distributing system but in an exhaust system the vacuum is necessarily 95 greater at the large or outlet end of the duct and the velocity of inflow therefore gradually increases toward the larger end of the duct. This may be allowed for in dimensioning the duct. The duct may be tapered less but the width of the inlet slot and the distance of the apron from the side of the duct may be uniformly tapered so that the inlet area per unit of length will be progressively decreased toward the fan, thereby maintaining substantially the same volume of inflow per unit length of duct, the velocity of flow being highest at the end nearest the fan, and lowest at the end farthest from the fan, and being progressively and uniformly varying at points between.

100 The formula for the calculation of the equalized outlet duct is based on the theoretical velocity of fluid, which is eight times the square root of the head in feet. Following this law, water flows with a one foot head at a velocity of eight feet per second. For gases under average local conditions, 105 29.9" barometric pressure and 60° F temperature, the theoretical velocity in feet per second is approximately 66 $\frac{2}{3}$ times the square root of the head when the head or pressure is taken in inches of water. With one inch static pressure the velocity of flow should 110 be 66 $\frac{2}{3}$ feet per second. In practice the formula 115

mula has a coefficient of efflux which is based on actual experience. The equalizer outlet duct comprises a converging pipe in which the coefficient varies from 9/10 to .99, 5 which is substantially 1. The most uniform distribution is obtained in a converging pipe which, if 50 diameters long tapers to 1/50 of the area at the small end, and provided with a longitudinal slot the full length of 10 the duct, which is in width 1/50 of the large diameter. The maximum head and velocity in the duct is at the supply end of the duct. The velocity of delivery at the large end of the duct is reduced to the same velocity as 15 that at the small end of the duct by the provision of suitable resistance along a slotted outlet. In this construction, the static pressure does three separate things which are almost exactly equal in pressure value. One 20 part or 1/3 provides the velocity head for actual slot delivery. One part overcomes the friction in a converging pipe with a length 50 times the duct diameter, and 1/3 of the static pressure changes the direction of the 25 flow of the air from the duct to the slotted outlet around a thin sheet. Since the pressure lost by friction varies from zero at supply end to a maximum of 1 at the small end, and the pressure lost by friction in the 30 slot outlets, varies from a maximum of 1 at the supply end to zero at the small end, it follows that the delivery velocity is uniform the entire length of the outlet, and it also follows that the static pressure required to 35 produce the flow is substantially 3 times the theoretical velocity through a simple aperture.

Although but one specific embodiment of this invention has been herein shown and 40 described, it will be understood that numerous details of the construction shown may be altered or omitted without departing from the spirit of this invention as defined by the following claims.

45 I claim:

1. A duct of the class described uniformly tapered lengthwise and provided with a longitudinal slot for sidewise flow of fluid, and an apron extending along and over said 50 slot, being spaced from the walls of the duct and tapering in width to provide varying local friction complementing the friction in the duct to insure substantially the same sidewise flow of the fluid for the different 55 units of length of the duct.

2. A duct of the class described uniformly tapered lengthwise and provided with a slot 60 extending lengthwise of the duct, an apron extending along said slot but spaced from the walls of the duct and tapering in width in correspondence with the taper of the duct, and transverse partitions between said apron and the wall of the duct.

3. A duct of the class described uniformly 65 varying as to carrying capacity from end

to end thereof, and a walled outlet extending along the side of the duct to provide for sidewise flow of fluid into or out of the duct, the walls of said outlet varying in area from end to end of the duct to resist the 70 flow of fluid in order to compensate for the varying static pressure and carrying capacity of the duct at different points along its length, and thereby insuring a uniformly distributed flow of fluid through the side 75 of the duct.

4. A distributing duct, apertured for sidewise distribution of fluid, and an apron extending along the duct and arranged to provide local resistance to sidewise flow proportioned in complementary relation to the static pressures in the duct at different points of its length, thereby insuring substantially the same sidewise flow of fluid for the different units of length of the duct. 80

5. A distributing duct having a longitudinal slot, a wall extending from the side of the duct along said slot and varying in width from end to end of the slot to provide local resistance to sidewise flow, proportioned in complementary relation to the static pressures in the duct at different points of its length. 90

6. A distributing duct, having a longitudinal slot for sidewise distribution of fluid, and an apron extending along the duct adjacent the slot, overlapping and spaced from the wall of the duct and shaped to provide local resistance to sidewise flow proportioned in complementary relation to the static pressures in the duct at different points of its length, thereby insuring substantially the same sidewise flow of fluid for the different units of length of the duct. 95

7. A distributing duct, having a longitudinal slot for sidewise distribution of fluid, and an apron extending along the duct adjacent the slot, overlapping and uniformly spaced from the wall of the duct and shaped to provide local resistance to sidewise flow proportioned in complementary relation to the static pressures in the duct at different points of its length, thereby insuring substantially the same sidewise flow of fluid for the different units of length of the duct. 105

8. A distributing duct, having a longitudinal slot for sidewise distribution of fluid, and an apron extending along the duct adjacent the slot, overlapping and uniformly spaced from the wall of the duct and tapered to conform with the taper of the duct. 110

9. A distributing duct, having a longitudinal slot of uniform width for sidewise distribution of fluid, and an apron extending along the duct adjacent the slot, overlapping and uniformly spaced from the wall of the duct and tapered to conform with the taper of the duct. 115

10. A distributing duct, having a longi-

tudinal slot for sidewise distribution of fluid, an apron extending along the duct adjacent to the slot, overlapping and spaced from the wall of the duct and shaped to provide local resistance to sidewise flow proportioned in complementary relation to the static pressures in the duct at different points of its length, thereby insuring substantially the

same sidewise flow of fluid for the different units of length of the duct, and flow directing partitions in the space between said apron and duct wall. 10

Signed at Chicago this 18th day of November 1921.

BURT S. HARRISON.
